[57] CLAIM

The ornamental design for pair of handles for a power amplifier, as shown and described.

DESCRIPTION

FIG. 1 is a front perspective view of a handle of a pair of handles for a power amplifier showing my new design, shown separately for clarity of illustration;

FIG. 2 is a front perspective view of the other handle of a pair of handles for a power amplifier, shown separately for clarity of illustration; the broken line showing of the portions of the face plate of the power amplifier is for illustrative purposes only and forms no part of the claimed design;

FIG. 3 is a top plan view of FIG. 1, the bottom plan view being a mirror image thereof; the bottom view of FIG. 2 being identical;

FIG. 4 is a left side elevational view of the handle unit in FIG. 1, the right side elevational view of the handle unit in FIG. 2 is a mirror image thereof;

FIG. 5 is a front, elevational view of the handle unit in FIG. 1; and,

FIG. 6 is a right side elevational view of the handle unit in FIG. 1; the left side elevational view of the handle unit in FIG. 2 is a mirror image thereof.

The rear of the handle units forms no part of the claimed design.
